UNITED STATES PATENT OFFICE.

WILLIAM WHITE, OF LONDON, ENGLAND.

ELECTRIC SWITCH.

SPECIFICATION forming part of Letters Patent No. 449,188, dated March 31, 1891.

Application filed December 3, 1889. Serial No. 332,411. (No model.)

To all whom it may concern:

Be it known that I, WILLIAM WHITE, electrical engineer, a citizen of England, residing at Langside, Baker Road, Harlesden, in 5 the county of Middlesex, England, have invented a new and useful Improvement in Electric Switches, of which the following is a specification.

My invention relates to a simple and inexpensive construction of electric switch, so arranged that in one position it makes effective contact for closing the circuit to which it is applied, and that when it is moved a little from that position it automatically makes a 15 rapid and complete break of contact, as I shall describe, referring to the accompanying drawings.

Figure 1 is a vertical section. Fig. 2 is a plan, the cover and the handle above the line 20 X in Fig. 1 being supposed to be removed.

A is a strip of brass or other suitable metal, the two ends of which are divided by slits into three, or it may be more, parts, which are stepped in their length, so that the first 25 is a little longer than the second, the second than the third, and so on. These parts are bent down so that their ends are at the same level but at different radial distances from the center of the strip, which is fitted on a 30 central spindle M.

In order to strengthen the middle portion of the strip A through which the spindle passes, a piece J is fixed on it by rivets, solder, or otherwise. On a base G of insulating 35 material are fixed two diametrically-opposite contact-plates F, which are radially stepped in correspondence with the steps of the bent ends of the divisions of A, and have the edges of their steps sloped a little downward. In 40 the center of the base G is fixed a metal bush N, through which passes the spindle M. In a recess in the under side of the base G is a spring S, bearing against the bolt-head of the spindle M, so as to urge the spindle downward. Above the piece J the spindle M passes 45 through a hole in a metal washer K and in a handle-head L, of ebonite or other suitable insulating material, to which the washer K is

fixed by screws. In a recess at the top of the head L there is a nut screwed on the end of the spindle M. A pin R, fixed in the piece J, stands up into a circularly-slotted hole C, made in the washer K. Under the strip A there is a helical spring P, the one end of which is inserted into a hole in the bush N 55 and the other end into a hole in the strip A, the spring being so set as to bring the strip A into the closed position A'', (shown in Fig. 2,) in which position the circuit is open. The internal parts are covered by a hood H. 60

The two contact-plates F being connected, respectively, to the wires of the circuit to which the switch is applied, the operation is as follows: When it is desired to close the circuit, the head L is turned by hand, and the 65 pin R being at one end of the slot C the strip A is caused to turn with it in opposition to the spring P until the bent ends of A simultaneously reach the steps of the contact-plates F. By a little more force applied to 70 the head L the bent arms of A are caused to mount the slopes at the ends of the steps of F, the spring S yielding a little to allow the moving parts to rise until the stepped ends are in close contact with the plates F closing 75 the circuit. The switch is held in position by the strain of the spring S pressing the bent ends of A down on the plates F. When it is desired to open the circuit, the head L is turned backward until the other end of the 80 slot C reaches the pin R and begins to move the strip A along with the head. After a little motion enough to release the bent ends of A from their strain on the plates F the spring P causes the strip A to make a rapid movement, and thus the bent ends of A are almost 85 instantaneously removed from contact with the plates F, and the circuit is opened.

Having thus described the nature of my invention and the best means I know for carrying the same into practical effect, I claim—

1. An electric switch consisting of central spindle M, movable longitudinally, on which are fitted an insulating-handle L, having a circular slot C, and a metal strip A, having its 95 ends stepped and divided and having a pin

R engaged in a slot C, in combination with springs S and P and with stepped contact-plates F, the whole mounted on an insulating-base G, substantially as described.

5 2. In an electric switch, stepped contact-plates having the edges of their steps sloped downward, in combination with correspondingly-stepped contact-arms and a shaft movable longitudinally and having a friction head 10 or shoulder, substantially as described.

In testimony whereof I have signed my name to this specification, in the presence of

two subscribing witnesses, this 15th day of November, A. D. 1889.

WILLIAM WHITE.
